UNITED STATES PATENT OFFICE

2,185,753

CARPET SWEEPER

John Percy Redfearn, Accrington, England, assignor to Entwistle & Kenyon Limited, Accrington, England

Application March 31, 1937, Serial No. 134,024
In Great Britain May 7, 1936

2 Claims. (Cl. 15—41)

This invention relates to carpet sweepers and more particularly to improvements in means for opening the dust pans thereof and maintaining them in the open position of the type in which the spring controlling the pans is connected at its apex to a link or wire extending upwards through a slot in the top of the sweeper casing and pivotally attached to an actuating lever on the top of the casing.

According to the present invention the apex of the two armed spring operating the two dust pans is connected to a link or a wire projecting upwards through a slot in the top of the casing in which it can have a lateral movement or the wire forming the spring is so bent that a vertical portion is formed above the apex and is extended upwards through the aforesaid slot, the upwardly extending link or wire or the extension of the spring being pivotally attached to an operating arm or lever fulcrumed at one end to a fixed pivot on the top of the casing whereby when the lever is raised from a horizontal to an approximately vertical position the pans are caused to open and the contents thereof discharged.

The invention will be described with reference to the accompanying drawings in which—

Fig. 1 is a plan view of one end of a carpet sweeper showing the invention applied thereto.

Fig. 2 is a transverse section on line 2—2 of Fig. 1 showing the dust pans closed.

Fig. 3 is a similar section to that shown in Fig. 2 but with the dust pans open for the discharge of the contents therefrom.

Fig. 4 is a side elevation of the operating arm or lever when in its upright position.

Fig. 5 is a horizontal section on line 5—5 of Fig. 2.

Fig. 6 is a detail view showing the connection between the V shaped spring and the upwardly projecting lever.

Fig. 7 is a detail view of a modification showing the V shaped spring connected to the operating arm or lever by a wire.

Fig. 8 is a detail view of a further modification in which the V shaped spring is extended upwards beyond its apex to connect it to the operating arm or lever.

The sweeper casing A, dust pans B, wheels C and brush D shown in the drawings are all of the usual construction, the dust pans B being pivotally mounted on pins b and connected together by a V shaped spring D.

One end of an operating arm or lever E is pivotally mounted in a bracket a affixed to the top

of the casing A, the bracket being formed with a rear member a¹ the edge of which adjacent to the fulcrum pin e² of the lever E limits the pivoting movement of the latter. A stop pin e³ is provided on the top of the casing A to prevent the lever E from damaging and wearing into the surface of the casing. A depending arcuate link F (Figs. 1 to 6) a bent wire F¹ (Fig. 7) or an extension F² of the V shaped spring D (Fig. 8) is pivotally mounted on a transverse pin or pivot e¹⁰ carried by the arm or lever E and passes through a slot a² in the top of the casing A, the link F or wire F¹ being loosely connected at its lower end to the apex of the V shaped spring D. The slot a² is sufficiently long to allow of the necessary lateral movement of the link F, wire F¹ or extension F². When the link F (Figs. 1 to 6) is employed it is formed with a projection f having a slot f¹ or hole therein in which the apex of the spring D is located whilst if a wire F¹ (Fig. 20 7) is employed it is formed with a bent end or eye f² to receive the apex of the spring D.

The edge nearer the fulcrum pin of the rear member a¹ of the bracket a forming the stop from the lever E is preferably situated so far to the rear of the pivot pin a² on which the arm or lever E is mounted to allow the arm or lever to pass beyond the vertical into the position shown in Fig. 3 with the pivot pin e on which the link F, wire F¹ or extension F² is mounted beyond the dead centre of the apex of the spring and the fulcrum thereby preventing the dust pans B from closing after they have been opened except by operation of the lever E.

The lever E is preferably of channel shape as shown in Figs. 4 and 6 with the pivot pin e extending across the two side members of the channel, its free end a¹ being suitably shaped and inclined to enable it to be engaged easily by the thumb or finger of the person operating it.

Two pins b¹ projecting inwardly from the end of the sweeper casing A are provided to form stops or abutments to limit the opening movement of the dust pans B as shown in Fig. 3.

By locating the position of the pivot pin e when the lever E is in its horizontal position, i. e., the position shown in Fig. 2, to one side of a vertical line through the apex of the V spring D and attaching the latter to the connecting link F, wire F¹ or extension F² so that the latter can move in relation thereto as shown in the drawings, one pan B will open before the other thus allowing the dust or litter to be discharged from one pan at a time in a desired direction. When the lever E is moved to close the dust pans B

the downward pressure of the apex of the spring D produced by the tendency of the two arms of the spring to open will ensure that the pans close properly and that the lever E returns to its horizontal position.

What I claim as my invention and desire to protect by Letters Patent is:

1. Mechanism for operating the dust pans of carpet sweepers comprising a casing, a bracket affixed on the top of the casing, an operating lever pivoted at one end to the bracket, a member on the bracket to prevent the operating lever from pivoting beyond a substantially vertical position, a V spring, dust receptacles to which the ends 10 of the V spring are pivotally connected, pivots for the dust receptacles carried by the casing, pins on the casing to prevent the dust receptacles from opening more than a predetermined amount, a link pivoted by one end to the actuating 15 lever intermediate its ends and depending through a slot in the casing and means for attaching the apex of the V spring to the lower end of the link whereby when the lever is raised to the substantially vertical position to fully open the 20 dustpans the point of attachment of the link to the lever passes the dead centre position and prevents the dustpans from closing until operated again by the lever.

the lever passes the dead centre position and prevents the dustpans from closing until operated again by the lever.

2. Mechanism for operating the dust pans of carpet sweepers comprising a casing, a bracket 5 affixed on the top of the casing, an operating lever pivoted at one end to the bracket, a member on the bracket to prevent the operating lever from pivoting beyond a substantially vertical position, a V spring, dust receptacles to which the 10 ends of the V spring are pivotally connected, pivots for the dust receptacles carried by the casing, pins on the casing to prevent the dust receptacles from opening more than a predetermined amount, an arcuate link pivoted by one 15 end to the actuating lever intermediate its ends and depending through a slot in the casing and means for attaching the apex of the V spring to the lower end of the link whereby when the lever is raised to the substantially vertical position to 20 fully open the dustpans the point of attachment of the link to the lever passes the dead centre position and prevents the dustpans from closing until operated again by the lever.

JOHN PERCY REDFEARN. 25
